FILLING CONTROL FOR BOBBIN CHANGING LOOM

Paul C. Consoletti, Milford, and Ronald Berry, Hopedale, Mass., assignors to Draper Corporation, Hopedale, Mass., a corporation of Maine

Application September 17, 1956, Serial No. 610,082

15 Claims. (Cl. 139—256)

This invention pertains to improvements in automatic looms, and more particularly, to a novel means for disposing of the filling ends from the ingoing and outgoing bobbins in a bobbin changing loom in a manner to prevent them from entangling with each other and to keep them from entering the shed to become woven into the fabric.

It is a general object of the invention to provide air operated and controlled means for disposing of the severed end of an outgoing filling thread and also to cut and to dispose of a similar end from the ingoing bobbin.

A further object is that of providing a novel timer means to control the start and the duration of the time period during which an air system shall function at each transfer cycle to perform its intended function.

A further object is that of operating a cutter for an ingoing thread by air during the replenishing cycle and to cut a filling end held in a thread disposal tube since the previous transfer.

Another object is that of assisting in the action of a thread disposal tube by supplementing it with a compressible thread holder.

A further object is that of devising an air operated cutter which shall function to trap a thread at one transfer cycle and cut it at the succeeding cycle.

Other objects will become apparent from the following more detailed disclosure.

In bobbin changing looms a cutter, preferably of Stafford type, is utilized to sever and to hold an end of an outgoing thread. That thread extends to the selvage at first, but is soon cut there by the temple thread cutter and the end which will be held at the binder portion of the cutter released at the next transfer may be disposed of by a suction tube in a known manner.

The ingoing filling end is normally attached at a knob or the like at the battery end and when cut at the selvage after the shuttle has made a few picks with the new filling supply, is freed to hang from the knob and is very likely to interfere with the outgoing thread or may become caught and pulled into the fabric at times. Various schemes have been advanced to take care of this end of ingoing thread.

According to the instant invention, this ingoing thread is so handled that as soon as it is severed to be released at the selvage, it is drawn into a suction tube and is held thereby until the succeeding transfer at which it is cut adjacent the knob or outer end of the battery to be released for discharge by the air system.

These two means are so disposed and controlled as to function in properly timed relationship by a timer and valve member preferably a part of the air pressure system so that all parts and functions are coordinated to carry through the cycle in an efficacious manner.

The invention will be described in greater detail by reference to one specific embodiment thereof as illustrated in the accompanying figures of drawing wherein:

Fig. 1 is a perspective view of the invention and attendant parts of a loom to which it applies.

2

Fig. 2 is a front elevation of the mechanism of Fig. 1.

Fig. 3 is a section showing details of a combined air valve and timer.

Fig. 4 is a plan view of a cutter and operating means therefor.

Fig. 5 is an end view of the parts shown in Fig. 4.

Fig. 6 is a section through an air injector and a side elevation of the cutter.

Fig. 7 is a plan view of a modification applied to a thread remover.

Fig. 8 is a front elevation of the device of Fig. 7.

Fig. 9 is a sectional view showing parts of Figs. 7 and 8.

Fig. 10 is a view to a larger scale illustrating details of a thread holding means.

Now referring to Figs. 1 and 2, the invention applies to the battery end of a fly shuttle loom having a loom-side 20 with a battery generally indicated at 21 which is of the usual construction found in Draper looms. It is adapted to be indexed as bobbins or filling packages are transferred in succession as required to a loom shuttle 22. The latter is picked in the usual manner and a filling feeler (not shown) upon sensing near exhaustion of filling acts in a known manner to set in motion parts including a starter shaft 23 to initiate a transfer, so-called.

Upon such indication for transfer or replenishment, a transfer hammer 24 is swung under influence of the forwardly moving lay to project a full package into the shuttle and to expel the empty one.

As is known to those skilled in this art, each bobbin in the battery, some of which are seen at 25, has the end of its thread passed toward the battery end, engaged in a notch in the threaded guide rim 26 and then wound about a knob or thread holder 27.

The cycle of operation incidental to a bobbin transfer includes the cutting and binding or holding of an outgoing thread at transfer and also the cutting at the selvage of both the outgoing and the ingoing filling a few picks after transfer. The first of these is effected by a Stafford type cutter such as that shown in United States Patent 2,711,193, the last pick as extended from the selvage being cut and held in this cutter and binder. This thread is severed at the selvage a few picks later, that leaving an end in the binder which will be released at the next transfer.

The temple thread cutter also severs the ingoing thread at the selvage, generally a pick or two after it cuts the outgoing filling and that end then hangs from the knob 27, and since it is fairly long, there is considerable danger that it will become entangled with mechanical parts, be caught by the shuttle, broken and dragged into the fabric, or entangled with the end of the outgoing thread. To take care of this end of the ingoing filling and also to dispose of the cut end from the outgoing thread an air operated cutter and attendant suction disposal tubes of novel characteristics are provided. The control for these air operated devices is also a part of the pressure system and functions to time the cycle automatically.

Again referring to Figs. 1 and 2, air under pressure is introduced to a combined valve and timer 28 through pipe 29 and from the valve to an injector-suction chamber 30 through tube 31, hollow transerrer stud 32 and tube 33. This injector-suction unit is illustrated in detail at Figs. 4, 5 and 6 and is of the venturi type; the air entering in tube 33 makes an exit at nozzle 34 which has at either side ports 35 and 36 through which air is drawn as the jet from the nozzle passes through the venturi chamber 37.

A tube 38 coupled to port 35 extends over to the inner side of the cutter and binder unit denoted by numeral 39. It is attached by a clip or the like to the inner end of the fixed bracket 40 of the cutter which is suspended from the transerrer stud 32 by an arm

and clamping hub 41. The open end of the tube is positioned at the side of the cutter blades and just out of contact with the front box plate at such time as the lay is forward. When the cutter moves in to cut the filling end the suction is induced more or less simultaneously and the end comes under the influence of the air stream entering the tube so that it is drawn into the tube to the extent permitted when first the end at the selvage is cut and then to fullest extent later when the cutter opens at the next transfer cycle. Of course, at that time it is ejected through the tube, port 35 and the venturi into a suitable receptacle 42. Such a receptacle may take the form of a cloth or other bag 43 of porous material which has its neck secured to a grommet 44 formed with a snap-loop 45 by which it may be easily attached or detached to or from the end of the venturi at which it is engaged in a groove 46.

The ingoing filling is cleared by cutting first at the selvage, drawing as much as possible into a suction tube and then cutting adjacent the thread guide rim after which it is discharged into the receptacle 42. To accomplish these functions, a special cutter is provided, this cutter being operable with an elongated blade 47 fixed to an arm 48 which, as herein shown, is a part of the upper portion of the injector-suction chamber 30. The blade extends under the thread so that those adjacent the lower or transfer position of the battery ride on top of the blade and the one from the bobbin next to be transferred enters a notch 49 at the top of the blade when a movable cutter 50 having a sharp edge 51 is in open position, Fig. 6.

An inclined thread trapping member 52 fixed to the side of the blade 47 opposite the movable cutter prevents the thread from missing the notch and, since it is inclined as shown, forces the thread down into the notch.

A suction tube 53 coupled to port 36 extends to a point adjacent the notch 49 as shown and is attached at its open end to the side of blade 47 by a clip 54. This clip is fixed in place by a bolt 55 which passes through a slot in the knife or cutter 50, is threaded through blade 47 and secured in adjusted position therein by a nut 55. A spring 56 and washer 57 between the bolt head and knife assure shearing pressure at the cutting edge. The knife is further slightly bent and also twisted so as to improve that function. The clip 54 is then held in place by nut 58.

The knife is operated by air pressure and for that purpose a cylinder 59 is sealed off by a cap or plate 60 screwed in place. A piston 61 and piston rod 62 are slidable in the cylinder and cap and the rod is connected to a bent end 63 of the knife. A spring 64 maintains the piston at the inner end of the cylinder and the knife in open position as in Figs. 4 and 6. When air pressure is introduced to nozzle 34 it also passes to the cylinder through port 65, overcoming spring 64 and pushing knife 50 along blade 47 past notch 49 to cut the thread therein.

The entire injector-suction unit 30, blade and cutter are mounted on a depending bracket 66. The unit has a short, faced extension 67 which attaches to a boss 68 at the lower end of the bracket which is itself clamped to the end of transfer stud 32 by its hub 69.

The air under pressure introduced at tube 29 is controlled by a valve and timer, Figs. 1 and 3. An elongated cylinder 70 is threaded into a T-like coupling member 71, and, in turn, a second cylinder 72 is threaded to the end of the first. Air enters the coupling 71 at 73 through tube 29 and the cylinder 70 through port 74.

A stem or piston rod 75 passes through a clearance hole in the coupling and also one in the end 76 of the first cylinder. It extends into the second cylinder and is fixed to its end a piston 77 which has considerable clearance within the cylinder and a pump or cup type washer 78 fixed to it to provide a tight seal in one direction. This washer is held in place by a screw and washer as shown.

The piston rod also has a collar 79 provided at an appropriate point along its length which acts against an O-ring 80 held in a recess in the face of the coupling which forms one interior surface of the cylinder 70. Under the influence of spring 81 which surrounds the rod and is under compression between the collar and a washer 82, the rod is forced in a direction to compress ring 80 and thus to seal off the cylinder 70 from an exit port 83. The clearance hole about the rod does permit a substantial flow when the rod and collar are so moved as to release pressure on ring 80.

An O-ring 84 recessed in the bore of the coupling seals it against leakage so that any air entering past ring 80 must flow out port 83 since the opposite end is closed. The washer 82 bears against an O-ring 85 which presses against the inner face of the end 76 of the first cylinder and is constricted about the piston rod.

Piston 77 has considerable clearance within the cylinder 72, while cupped washer 78, when pushed to the right, Fig. 3, will let air by, but will not permit its passage in the opposite direction.

Cylinder 72 has one or more perforations 86 which permit air to enter behind piston 77 as it is moved to the right, and also provide an air exit when parts return under influence of spring 81.

A plug 87 made of a suitable pervious material such as sintered metal, ceramics or wood with the grain lengthwise of the cylinder is tightly set in the end of the second cylinder. This plug serves to admit air from the outside to the space within the cylinder and at the piston head so that when moved to the right, Fig. 3, the air in this head space passes by cupped washer 78 and a very small amount thereof passes out the plug 87 to evacuate this space. Upon release, the spring tends to return the rod and piston to its initial position, but the vacuum at the piston head is such that movement is resisted and is largely governed by the plug 87 which controls the inflow of air. By varying one or more of the parts, the time during which the valve shall remain open may be regulated from a matter of a few seconds to one of minutes.

This timer and valve are set from the starter shaft 23, Fig. 1, and the swinging movement of that shaft is conveyed to the rod 75 by a spring arm 88. The latter presses inwardly on the said rod pushing it and the piston to more or less their extreme position. The flexibility of the arm makes it possible for the starter rod to make an added movement without affecting the timer after the latter has become fully set.

Of course, the starter shaft returns to its original position soon after transfer, but the timer delays the closing 50 of the valve so that air pressure passes through between collar 79 and ring 80 for any reasonable period required to take care of the thread disposal when the ends at the selvage are cut by the temple thread cutter.

As described to this point, the Stafford type cutter severs and holds an end of the outgoing filling after which that end is drawn into the tube 38 when cut at the selvage. The tube, of course, does not move and the thread must be brought forwardly into range of the tube end to assure its being caught by the air stream. In the event the Stafford cutter severs but does not hold the end, it is very likely to be missed by the suction since it will drop or fly about wildly and will not get into range of the tube end. Again, if there should be some slack in the end held by the cutter and running to the selvage, since there are about four inches to the tube end, it may be missed.

These are all occurrences not at all likely to happen in a loom functioning properly, but to compensate for such difficulties if they should occur, a modification as in Figs. 7-10 provides a movable tube and a means at the end thereof to grip the thread before it is cut rather than after.

Specifically, a Stafford type cutter 89 is provided with an extra groove 90 for a second slide 91 which has a laterally extending bracket 92 to which is fixed the end 70 of a tube 38 by a clip 93. The usual link 94, when

actuated, moves both the cutter and the tube since it connects to a stud 95 fixed in both the slide 91 and the cutter slide 96, passing through a slot 97 in the web 98 of the double, grooved bracket 99.

A bellows 100 of rubber or a rubber-fabric composition is cemented or otherwise fastened to the tube end. It has sufficient rigidity to continue in substantially the direction of the tube and at the time the cutter moves in to get the outgoing filling, it engages against the front box plate registering with the usual slot therein and aligned with the filling as it lays along the shuttle length. The suction is, of course, applied at the time so the filling is actually drawn to and held by the air stream at the bellows end. Just after that the cutter enters the shuttle to sever and grip the filling. In the event of slack or failure of the cutter to hold, the thread has already been gripped so that the end may drop or the thread tend to sag without danger of its being missed by the suction tube, the cutter or both. When the cutter is retracted, the tube and bellows are also retracted. The thread is drawn into the tube or perhaps only the bellows to a slight extent at the time, but will be taken in and disposed of in later steps just as explained before.

To review the operation, the loom may be considered as running on a partially filled bobbin and at that time the outgoing end will be held at the Stafford cutter with considerable of its length being drawn into the tube 38 or 38', the ingoing thread end being drawn into the tube 53, but also lying in the notch 49 and extending out about rim 26 to knob 27.

At the indication for transfer starter rod 23 is rocked swinging arm 88 to press in the rod 75 to an extent depending upon the time interval for which it may be set. The air pressure is then admitted from cylinder 70 past the ring 80 to port 83 and by tube 31, hollow stud 32 and tube 33 to the nozzle 34 and venturi 37. This sets up suction in lines 38 and 53 and, of course, the timer cycle is started, the rod 75 beginning to return slowly as air is admitted through plug 87.

The Stafford type cutter moves in to cut and hold the outgoing end and opens to release the end from the previous transfer which is discharged into the bag 43. Either before or after its return, the outgoing end is caught by suction at the tube or bellows as the case may be. A few picks later the end is cut at the selvage and as much as can be is drawn into tube 38.

At the same time the above mentioned part of the cycle incidental to the outgoing thread is going on, the battery thread cutter and vacuum system for the ingoing thread are functioning. As soon as air is admitted to the system by the combined timer-valve, it also actuates piston 61 and thereby knife 50 to cut the filling which was sucked in at tube 53 on the previous transfer. When cut it is discharged to bag 43.

The new ingoing filling moves to a position above notch 49 being held from entering the notch since knife 50 will remain extended to cutting position as long as the air pressure is applied to the cylinder 59 and piston 61. That thread also lays up against guard 52 and falls to notch 49 when the piston and knife are retracted. Then when the ingoing end is cut at the selvage, as much of the end as can be is sucked into tube 53.

This completes the cycle leaving parts and thread ends in the position they occupy during the run between transfers and after the ends have been cut at the selvage. The timer closes the valve shortly after both threads have been cut at the selvage.

While one embodiment of the invention has been disclosed, it is to be understood that the inventive concept may be carried out in a number of ways. This invention is, therefore, not to be limited to the precise details described, but is intended to embrace all variations and modifications thereof falling within the spirit of the invention and the scope of the claims.

We claim:

1. In an automatic bobbin changing loom, a shuttle, a battery in which a plurality of filling packages are mounted, means for successively transferring said filling packages to the shuttle in response to an indication taken from a package nearing exhaustion, a cutter and binder for cutting and holding the outgoing thread, suction means for disposing of that thread when released by the binder, a second suction means for retaining a cut end of the ingoing thread and a cutter adjacent said suction means for severing that end to release it for disposal by said suction means and timer means for determining the period of time during which said suction means shall remain in operation.
2. In an automatic bobbin changing loom, a shuttle, a battery in which a plurality of filling packages are mounted, means for successively transferring said filling packages to the shuttle in response to an indication taken from a package nearing exhaustion, a cutter and binder for cutting and holding the outgoing thread, suction means for disposing of that thread when released by the binder, a second suction means for retaining a cut end of the ingoing thread and a cutter adjacent said suction means for severing that end to release it for disposal by said suction means and timer means set into operation by the means which indicates near exhaustion of filling for determining the period of time during which said suction means shall remain in operation.
3. In an automatic bobbin changing loom, a shuttle, a battery in which a plurality of filling packages are mounted, means for successively transferring said filling packages to the shuttle in response to an indication taken from a package nearing exhaustion, a cutter and binder for cutting and holding the outgoing thread, suction means for disposing of that thread when released by the binder, a second suction means for retaining a cut end of the ingoing thread and a cutter adjacent said suction means for severing that end to release it for disposal by said suction means, an air system including a valve and timer and means functioning therewith to actuate said cutter for the ingoing thread.
4. In an automatic bobbin changing loom, a shuttle, a battery in which a plurality of filling packages are mounted, means for successively transferring said filling packages to the shuttle in response to an indication taken from a package nearing exhaustion, a cutter and binder for cutting and holding the outgoing thread, suction means located at the outer end of said battery for disposing of an end of an ingoing thread, a cutter immediately adjacent said suction means for severing that thread to release it for disposal by said suction means and a common source of air pressure and means operable thereby for inducing negative pressure in said suction means and for actuating said cutter.
5. In an automatic bobbin changing loom, a shuttle, a battery in which a plurality of filling packages are mounted, means for successively transferring said filling packages to the shuttle in response to an indication taken from a package nearing exhaustion, a cutter and binder for cutting and holding the outgoing thread, a suction means for disposing of an end of an ingoing thread, a cutter for severing that thread adjacent a point at which its end is held at said battery, and a timed means functioning from a source of air under pressure for inducing negative pressure in said suction means and for actuating said cutter.
6. Mechanism as defined in claim 5 wherein said timed means comprises a valve and a timer operatively associated therewith, said timer operating under the influence of an air displacement means.
7. In an automatic bobbin changing loom, a shuttle, a battery in which a plurality of filling packages are mounted, means for successively transferring said filling packages to the shuttle in response to an indication taken from a package nearing exhaustion, a cutter and binder for cutting and holding the outgoing thread, suction

means for retaining an end of the ingoing thread; a cutter adjacent said suction means for severing the ingoing thread to release it for disposal by said suction means, a cylinder and a piston for actuating said cutter, a source of air pressure and means connecting said pressure to the cylinder and other means through which said air is conducted for inducing subatmospheric pressure in said suction means.

8. In an automatic bobbin changing loom, a shuttle, a battery in which a plurality of filling packages are mounted, means for successively transferring said filling packages to the shuttle in response to an indication taken from a package nearing exhaustion, a cutter and binder for cutting and holding the outgoing thread, suction means for retaining an end of the ingoing thread, a cutting means comprising a blade, a notch in said blade, a knife cooperating with said blade and notch to sever the ingoing thread to release it for disposal by said suction means, a cylinder and piston for actuating said cutter, a source of air pressure and means connecting said pressure to the cylinder and other means through which said air is conducted for inducing subatmospheric pressure in said suction means.

9. Mechanism as defined in claim 8 wherein a guard is positioned at one side of said notch to stop the thread in position to fall into said notch when the knife is moved from the notch.

10. In an automatic bobbin changing loom, a shuttle, a battery in which a plurality of filling packages are mounted, means for successively transferring said filling packages to the shuttle in response to an indication taken from a package nearing exhaustion, a cutter and binder for cutting and holding the outgoing thread, suction means for disposing of that thread when released by the binder, a second suction means for retaining a cut end of the ingoing thread and a cutter for severing that end to release it for disposal by said suction means and timer means for determining the period of time during which said suction means shall remain in operation, said timer means comprising a cylinder, a piston movable in said cylinder, spring means to bias the piston toward one end of the cylinder, air exhaust ports in the cylinder at one end of the piston and a plug of porous material at the other for slowly permitting the bleeding of air to the cylinder.

11. Mechanism as in claim 10 wherein said plug is of sintered metal.

12. In an automatic bobbin changing loom, a shuttle, a battery in which a plurality of filling packages are mounted, means for successively transferring said filling packages to the shuttle in response to an indication taken from a package nearing exhaustion, a cutter and binder for cutting and holding the outgoing thread, a suction means for disposing of that thread when released by the binder, and means comprising a deformable extension movable to a position overlying the outgoing thread at the shuttle for engaging said thread before it is severed.

13. In an automatic bobbin changing loom, a shuttle, a battery in which a plurality of filling packages are mounted, means for successively transferring said filling packages to the shuttle in response to an indication taken from a package nearing exhaustion, a cutter and binder for cutting and holding the outgoing thread, means for moving said cutter and binder toward the shuttle at transfer, a suction tube movable toward the shuttle with said cutter and binder for disposing of said thread when released by the binder, a deformable member forming an extension of said tube movable with it to a position adjacent the thread at the shuttle for holding that thread prior to its being severed by the cutter thereby to facilitate and assure its entrance into the tube whenever released.

14. Mechanism as defined in claim 13 wherein said deformable member comprises a tube of rubber-like material of such length as to be compressed slightly when the parts are in position at the transfer cycle.

15. Mechanism as defined in claim 13 wherein said deformable member comprises an accordion tube of rubber-like material fixed to the end of said suction tube.
